UNITED STATES PATENT OFFICE.

JOHN J. SNYDER, OF CHICAGO, ILLINOIS.

CREDIT-REGISTER.

1,164,883.

Specification of Letters Patent. Patented Dec. 21, 1915.

Application filed April 27, 1914. Serial No. 834,576.

To all whom it may concern:

Be it known that I, JOHN J. SNYDER, a citizen of the United States, and a resident of Chicago, in the county of Cook and State of Illinois, have invented certain new and useful Improvements in Credit-Registers, of which the following is a specification.

This invention relates to a device in which duplicate copies of sales slips or accounts are to be filed and indexed.

The objects of my improvements are to produce a simplified credit register that can be manufactured at a minimum cost, and still be as effective and handy in its operation as the more expensive ones now being made, and a register in which a large number of sales slips can be filed in as small and compact a space as possible, so the register may be placed in an ordinary sized safe, in order that the merchant's accounts may be protected against loss by fire.

In the drawing Figure 1 shows the register in an operative position. Fig. 2 shows the construction of the removable index without the index cards in place on same. Fig. 3 shows the follow-stop, removed from the register.

Similar numbers refer to similar parts throughout the several views.

Fig. 1 is a view of the register in position ready for use, with the body 1 of the register resting in the inverted top 2 of the same. A represents index cards in the register, between which the sales slips or accounts are filed.

Fig. 2 shows the construction of the removable index, without the index cards in place on same. The frame of the index 10 is preferably formed of one piece of metal. 11 are two spring steel wire guides on which the index cards are mounted, and which are attached rigidly to the frame at their lower ends but are not attached to the frame at their upper ends 12, in order that any one of the index cards can be removed and replaced by another card when necessary, by simply pulling the upper ends of the spring wires out a little from the frame. At 12 there are two round sockets drilled half way through the frame, for the ends of the spring wire guides to enter, so there is no interference or place for the cards to catch when operating the index. B shows the index cards in place on the index frame. The index is operated by turning up and exposing to view any card desired for ref-

erence, the card or cards so turned up being held against the frame, and when these cards are released they fall back in place as shown in the drawing at B, because the upper end or arch of the frame leans forward just a little over the center of gravity. In order that the index can be easily operated with the finger of one hand, the lower ends or lower portion of the cards extend down, outward and away from the frame, so that by pressing downward on any one card with one finger, the cards are separated at the place desired and are handily shoved up against the upper end or arch of the frame so as to be in view. When the register is not in use and it is desired to place it in a safe for fire protection, the index B is simply lifted out of the register, as the two legs or standards 10 of the index are detachably engaged within the guide-ways 9 arranged at the rear corners of the register. When the index B has been removed from the register, the body of the register 1 is lifted out of the inverted top 80 of the register 2, and the top put on the register, when the register is ready to be placed in a safe. The top is held in place at the front end of the register by the catch 3 provided on the body and engaging the staple 85 4 on the top member. 5 shows a handle on the front end of the register. When the top is on the register, it can be carried by the handle 5.

The register is operated in the following manner: The cards on the upper index B are indexed alphabetically. The name of each person having an account is written on these cards, each account having a number. The cards in the register A are indexed by 90 numbers, (with the exception of a few cards in the front part of the register that are indexed by letters, for transient accounts) the numbers being located on little projections or ears, which can be removed from the 95 cards, and below these projecting numbers the customer's name and address is written across the top of the card. To find any person's account, his name is first found on the alphabetical index B, and opposite his name is found his number. His account is then located in the register by his number.

This index is simple and cheaply constructed, yet effective and handily operated. It can be quickly placed in the register for operation, or quickly removed from it at the close of the day's business by simply

lifting it out, when the register top can be put on the register and the register placed in a safe. If the index should be destroyed by fire, the loss would be small, because the 5 merchant could obtain another one and fill in the names of his customers and the respective numbers of their accounts; but if the register containing his accounts should be destroyed, his loss would be the same as 10 having his day-book, journal and ledger destroyed; because the credit register system of handling accounts does away with book-keeping; the duplicate sales slip of the customer's last purchase or transaction is a 15 statement of his account showing his balance due totaled and brought forward to the time of his last purchase. I claim no invention as to the manner in which the accounts are handled in this register, and mention this point only to show the advantage 20 of a register as small and compact as possible, so it can be placed in a small size safe.

Fig. 3 shows the follow-stop removed from the register. 8a—8a is a rod which 25 forms the upper part of the follow-stop, and 8 is a plate or shield forming a part of the follow-stop (preferably made of thin sheet metal) against which the index cards lean and are prevented from falling forward in 30 the register. The follow-stop is held in place by the two projecting ends of the rod 8a—8a fitting in the half round bead or groove 6 on each side in the register, the two ends of the rod resting against the stops 7 35 intersecting each of the grooves 6 and which hold the follow-stop firmly in place. The follow-stop is moved forward short spaces at a time as the sales slips increase, by first moving backward either end of the rod 8a, 40 and taking the follow-stop out, and replacing it again as desired. The shield or plate 8 of the follow-stop is made the proper length so that the bottom of it rests on the bottom of the register, so as to have it lean 45 slightly and in the proper position for the index cards to lean against. The rod 8a—8a alone, (which could be a straight rod, or curved downward in the middle to rest on the bottom of the register) would serve as 50 a follow-stop, but I prefer the construction as shown in the drawing; that is, the shield 8 attached to a straight rod.

This follow-stop for the index cards occupies the smallest possible space in the register. This follow-stop is constructed so it 55

can be removed from the register when the register becomes full of sales slips, thus providing more space in the register which can be utilized when necessary.

From the foregoing description, it is 60 thought to be obvious that a credit register constructed in accordance with my invention is of an extremely simple and comparatively inexpensive nature and is particularly well adapted for use by reason of the convenience 65 and facility with which it may be assembled, and it will also be obvious that my invention is susceptible of some change and modification without material departure from the principles and spirit thereof and 70 for this reason I do not wish to be understood as limiting myself to the precise arrangement and formation of the several parts herein shown in carrying out my invention in practice, except as defined by the 75 appended claims.

Having described my invention I claim:

1. In an account register, a filing case for sales slips, index guide cards therein, and a separate index device removably secured to 80 said filing case and consisting of a frame, two guide members attached at their lower ends to said frame, and index cards mounted on said guide members, said frame having a back portion with holes adapted to removably receive the upper ends of said 85 guide members and to form a stop against which any portion of the group of index cards may be held while referring to any particular card, said stop being in such a 90 position that the cards fall downwardly into their lowermost positions when released.

2. In an account register, a filing case for sales slips, index guide cards therein, and a separate index device removably secured to 95 said filing case and consisting of a frame, two guide members attached at their ends to said frame, and index cards mounted on said guide members, said frame having a back portion to form a stop against which any 100 portion of the group of index cards may be held while referring to any particular card, said stop being in such a position that the cards fall downwardly into their lowermost positions when released.

JOHN J. SNYDER.

In presence of—

JULIA F. ADAMS,
EMIL A. ASHRING.
